United States Patent

Des. 238,126
Patented Dec. 23, 1975

238,126

BRUSH

Robert A. O'Neil, Wheaton, Ill., assignor to Kellogg
Brush Manufacturing Co., Easthampton, Mass.

Filed Mar. 1, 1974, Ser. No. 447,078

Term of patent 14 years

Int. Cl. D4—01

U.S. Cl. D4—1

FIG. 1.

FIG. 2.

FIG. 3.

FIG. 4.

FIG. 1 is a top plan view of a brush showing my new design;

FIG. 2 is a bottom plan view thereof;

FIG. 3 is a side elevational view thereof; and

FIG. 4 is an end elevational view thereof, the opposite end being substantially a mirror image thereof.

I claim:

The ornamental design for a brush, as shown and described.
